DRESS SHOE COVER

Rosilda C. Savale, West Orange, N. J.

Application June 15, 1934, Serial No. 730,710

7 Claims. (Cl. 36—1)

The invention relates to dress shoe covers, and more particularly to a cover which is so constructed as to be snugly fitted to and firmly secured about the upper of an ordinary dress shoe 5 so as to permit the completion of the ensemble of the costume by a matching of the color of the shoe with that of the material of a dress.

In the cycles of the modes, so far as they relate to costumes for women, there is a recurrent 10 fashion demanding that the same color scheme or a complementary color scheme, be extended throughout an outfit including dress, hat, gloves and shoes. This fashion ordinarily demands that shoes be matched in color with each dress, 15 and by reason of the practice of wearing the same dress only a few times, shoes because they are more or less costly are a very expensive element in the wardrobe. Furthermore, the short period of their use as determined by the life of 20 a dress with which they are worn, does not permit the wearing of shoes throughout what would be the normal life of the shoe, particularly as shoes of a light, delicate color soil readily. Hence, the life of dress shoes for women is determined largely by their appearance. 25

With the above conditions in mind, I have provided a dress shoe cover, which can be fitted to the upper of an ordinary shoe and so firmly secured in position that to all intents and purposes, it becomes a part of the shoe, since the means of attachment is practically invisible except upon the closest inspection.

With a cover embodying the invention, it is possible, at very small expense, to match the 35 same pair of shoes with any costume, since the same material of which the dress is made may be employed in the making of the cover. With the use of such a cover, the upper of the shoe itself is so protected that it will not become soiled 40 and by using, with the same pair of shoes, covers of different colors, full advantage may be taken of the normal durability of a pair of shoes.

In this manner, it is possible to adapt oneself to the prevailing mode as to the matching 45 of shoes with dresses, at comparatively small expense, since a considerable number of covers may be produced at a cost less than that of one pair of dress shoes.

The cover of the invention does not project over the sole or the heel of the shoe, so that when in use, except for the means positioned under the shank for firmly attaching the cover to the 50 shoe, the appearance of an ordinary shoe is se-

cured and no part of the cover is subjected to wear from walking or dancing.

The construction of the cover is such as to permit it to be readily and conveniently applied to, and removed from, a shoe, and the number 5 and form of the parts embodied therein are such as to permit the production of the cover at small cost.

The invention consists primarily in a dress shoe cover embodying therein an upper open at 10 the top and at the bottom, an elastic member about the open bottom of the upper and so formed as to fit a shoe above the sole, and means, separable from the shank of the shoe and from said upper, adapted to pass below said shank 15 and engage said elastic member at opposite sides thereof and contract said member adjacent the shank of a shoe; and in such other novel characteristics as are hereinafter set forth and described, and more particularly pointed out in 20 the claims hereto appended.

Referring to the drawing,

Fig. 1 is a side view of a shoe having a dress shoe cover embodying the invention applied thereto, portions of said covering being broken 25 away;

Fig. 2 is a bottom plan view of the shoe;

Fig. 3 is a section on the line 3—3 of Fig. 1;

Fig. 4 is a view of the wire frame of the cover; and

Fig. 5 is a perspective view of the preferred 30 form of means for contracting the wire frame.

Like numerals refer to like parts throughout the several views.

In the embodiment of the invention shown in 35 the drawing, it is illustrated in connection with a well known form of dress shoe having an upper 10, a sole 11, heel 12 and shank 13. In such shoes, which are ordinarily turned shoes, there is a slight depression about the upper at the channel 40 about the sole, and I take advantage of this depression, in the use of the cover of the invention, in attaching the cover to the shoe without such ungainliness at the point of attachment as to pronouncedly indicate the presence of the cover. 45

The cover of the invention itself consists of a fabric upper, the pattern of which corresponds with the ordinary upper of a shoe and has the usual seams. The fabric of the upper of the cover is indicated at 14, this upper being open at 50 the top and at the bottom thereof as well, so that the sole 11, heel 12 and shank 13 are exposed through the bottom of the cover when it is in place on a shoe.

About the open bottom of the cover 14 is a nar- 55

row hem 15 in which is held a frame 16 of small gauge spring wire. The ends of this wire are united at 17 by welding, or in any other desired manner, so as to have a continuous wire frame 5 extending entirely about the bottom of the upper and of a size to closely fit within the depression or groove at the juncture of the upper 10, and the sole 11 and heel 12. The open top of the upper of the cover is also provided with a narrow hem 18 in which a takeup elastic or draw cord 19 10 is positioned. The vamp of the cover should be slightly longer than that of the shoe, and the back quarter of the cover should be slightly higher than that of the shoe. No counter is used in the cover, 15 so that when not in use it will collapse and occupy but little space.

The wire frame 16 is preferably made of spring metal of a sufficiently small gauge to form no appreciable bulge about the sole and the heel of 20 the shoe.

I have found that with the use of the wire frame 16 alone, there is a tendency of the cover to creep upwardly away from the sole and expose a narrow strip of the upper below the cover. In 25 order to obviate this, it is necessary to contract the frame 16 in a manner to cause it to tightly embrace the shoe and to fit snugly within the slight depression at the juncture of the upper 10 and the sole 11 and heel 12. If, in the manu- 30 facture of shoes, the channel about the sole is deepened as compared with the ordinary channel, a wire of larger gauge may be used and a better fit of the frame to the shoe can be secured.

When spring wire is used, contraction of the 35 frame at all points thereof may be secured by drawing together the opposite sides of the frame positioned at the shank. With a dress shoe having an ordinary French heel, ample space is provided below the shank for the means used for 40 thus contracting the frame, and such means are sufficiently concealed to avoid any objectionable appearance in the cover.

Preferably, I employ a contracting plate 20 of 45 a width slightly greater than that of the shank 11 passing below the shank of a shoe and separable therefrom and from the upper, this plate, having upon the opposite sides thereof flanges 21 and 22 forming channels adapted to embrace the edges 50 of the shank and the portions of the wire of the frame adjacent thereto. Like the shank itself, the plate 20 tapers toward the toe of the shoe, so that in attaching the plate there is a wedging action having the two-fold result of drawing the 55 opposite sides of the frame toward the shank and attaching the plate to the shoe sufficiently securely to prevent accidental displacement thereof when walking or dancing. While other contracting means may be employed, I have found the plate 20 to be particularly suited for this purpose.

With a cover such as is herein described, it is 60 possible to produce wire frames 16 of different sizes to conform to different sizes of shoes, and to so form the plates 20 as to adapt them to different sizes of wire frames.

The frames 16 and plates 20 may be made as 65 distinct articles of manufacture, so that a person desiring to produce the covers may take the same material as that from which a dress is made, and by the use of suitable patterns, make an upper 14 which matches exactly, in color and material, the dress with which the shoes carrying the cover are to be used. The forming of the hems 15 and 70 18 is an ordinary machine stitching operation,

and the frame 16, when included within the bottom hem 15, ensures a proper sizing of the bottom of the upper of the cover. An elastic or draw cord included in the upper hem 18 ensures a proper fit of the top of the cover to the foot. The greater length of the vamp and height of the back quarter 5 of the upper of the cover is to permit the material of the upper 14 to overlay the top of the upper of the shoe proper, so as to conceal the shoe when a cover is used thereon.

After the completion of the cover, the shoe is slipped toe first through the open top of the cover and the frame 16 fitted by hand about the channel of the sole. The plate 20 is then engaged with the opposite sides of the wire frame adjacent the 15 shank and slid toward the heel until it is firmly wedged in position. As it moves rearwardly, the tapered flanges 21 and 22 of the plate engage the wire of the frame 16 toward the toe of the shoe.

It is customary, in ladies' shoes, to give a certain arch to the shank, and a corresponding arch must be given to the plate 20 in order to secure the desired snug fit between this plate and the under face of the shank.

In ladies' dress shoes the heel covering sometimes conforms to that of the upper and sometimes is of a neutral color, or is decorated with rhinestones. With the cover of the invention, it is obvious that it will be necessary to provide heels having covers of neutral colors, such as gold 30 or silver or decorated with stones as above stated, since no provision is made in the cover for conforming the color of the heel to the upper of the cover.

With the use of covers as described, the same 35 shoes may be used with a variety of different dresses, and by the use of different covers, each time the shoes are worn they may be matched with the material of different dresses. If desired, in travelling to or from a place of entertainment, 40 covers embodying the invention may be used solely for the purpose of protecting the shoe from accidental soiling thereof.

It is not my intention to limit the invention to the precise details of construction shown in the 45 accompanying drawing, it being apparent that such may be varied without departing from the spirit and scope of the invention.

Having described the invention, what I claim as 50 new and desire to have protected by Letters Patent, is:—

1. A dress shoe cover embodying therein an upper open at the top and at the bottom, an elastic member about the open bottom of the upper and so formed as to fit a shoe above the sole, and means, separable from the shank of the shoe and from said upper, adapted to pass below said shank and engage said elastic member at opposite sides thereof and contract said member adjacent the shank of a shoe.

2. A dress shoe cover embodying therein an upper open at the top and at the bottom, an endless spring wire frame conforming in contour with the bottom of the upper adjacent the sole of the shoe, and connected adjacent the open bottom of the upper, and means, separable from the shank of the shoe and from said upper, adapted to pass below said shank and engage said frame upon opposite sides of the shank and contract said frame adjacent the shank of a shoe.

3. A dress shoe cover embodying therein an upper of fabric so patterned as to snugly fit the upper of a shoe, said upper being open at the top and at the bottom thereof, and having a vamp of greater length, and a back quarter of greater 75

- height, than that of the shoe upper to which the cover is to be fitted, hems about the open top and the open bottom of said upper, takeup means in the hem about the top of the upper, a flexible 5 wire frame in the hem about the bottom of the upper, said frame being so formed as to fit a shoe above the sole, and means for contracting said wire frame adjacent the shank of a shoe.
4. A dress shoe cover embodying therein an upper open at the top and at the bottom, a flexible wire frame about the open bottom of the upper and so formed as to fit a shoe above the sole, and a contracting plate of a width slightly greater than that of the shank of the shoe, and having 10 upon opposite sides thereof channel forming flanges adapted to embrace the edges of the shank portion of a shoe and portions of the wire frame adjacent said shank portion.
5. A dress shoe cover embodying therein an upper open at the top and at the bottom, an endless spring wire frame conforming in contour with the bottom of the upper adjacent the sole of a shoe, and connected adjacent the open bottom of the upper, and a contracting plate of a width 15 slightly greater than that of the shank of a shoe, and having upon opposite sides thereof channel forming flanges adapted to embrace the edges of the shank portion of a shoe and portions of the wire frame adjacent said shank portion.
6. A dress shoe cover embodying therein an upper of fabric so patterned as to snugly fit the upper of a shoe, said upper being open at the top and at the bottom thereof, and having a vamp 20
- of greater length, and a back quarter of greater height, than that of the shoe upper to which the cover is to be fitted, hems about the open top and the open bottom of said upper, takeup means in the hem about the top of the upper, an endless spring wire frame conforming in contour with the bottom of the upper adjacent the sole of a shoe, positioned in the hem about the bottom of 25 the upper, said frame being so formed as to fit a shoe above the sole, and a contracting plate of a width slightly greater than that of the shank of a shoe, and having upon opposite sides thereof channel forming flanges adapted to embrace the edges of the shank portion of a shoe and portions of the wire frame adjacent said shank portion.
